UNITED STATES PATENT OFFICE.

WALTER D. BRENNER, OF SMITHSBURG, MARYLAND.

GAME APPARATUS.

1,319,561.

Specification of Letters Patent.

Patented Oct. 21, 1919.

Application filed April 10, 1919. Serial No. 289,115.

To all whom it may concern:

Be it known that I, WALTER D. BRENNER, a citizen of the United States, residing at Smithsburg, in the county of Washington and State of Maryland, have invented certain new and useful Improvements in Game Apparatus, of which the following is a specification.

This invention has for its object to provide a game apparatus embodying such features of construction as to attract and retain the attention of the players and also instruct and educate the players in the correct spelling of words and assist in teaching elementary mathematics.

With these and other objects in view as will appear as the description proceeds, the invention comprises the novel features of construction, combination of elements and arrangement of parts which will be more fully described in the following specification and set forth with particularity in the claims appended hereto.

In the drawings:

Figures 1 and 2 represent a plan view of the gameboard,

Fig. 3 represents perspective views of the game pieces or cubes, and

Fig. 4 represents a modification of the game piece in the form of a card.

Referring to the drawing in detail, wherein similar reference numerals designate corresponding parts throughout the several views, the numeral 5 indicates a game board 35 preferably circular in form and constructed of relatively thin flat material having requisite strength and rigidity in order that it may withstand the use for which it is designed.

The top surface of the game board is marked with concentrically spaced inner and outer circles 6 and 7, dividing the area of the board into the central circular field or space 8, the intermediate annular space 9 and the 45 annular marginal space 10. A number of words of three or more letters are printed or otherwise marked in the central space 8 and beside each word is marked its numerical value, in accordance with the game. For instance, the numerical value of the word "boy" is 1, "cow" 2 and so on but it will be observed that before the numerals associated with the words "rat" and "cat" are found minus signs indicating that instead of taking credit for these words when it is possible to spell them with the game pieces

hereinafter described, the player is deprived of a number of counts corresponding to those associated with these two particular words. It will be noticed that both the 60 Arabic and Roman numerals are employed as designating the numerical value of the respective words in order to increase the educational value of the game.

The intermediate annular space 9 is divided by a series of equidistant radial lines 11 into eight segmental spaces 12 in which are printed or otherwise marked in relatively large letters A, E, I, O, U, W, Y, and G.

Cubical game pieces such as illustrated in Fig. 3 are used in connection with the board 5 in playing the game and the complete game apparatus preferably consists of seven of the cubical game pieces, three of which are 75 marked upon their sides with the letters of the alphabet exclusive of those which appear in the segmental spaces 12.

In playing the game, the three game pieces bearing the letters of the alphabet are 80 shaken in the manner of dice and thrown upon a board or other flat surface and the letters appearing upon the top of the game pieces are used in conjunction with those appearing in the segmental spaces 12 to construct such words as appear in the central circular space 8. For instance, should the letters P, B and J appear uppermost when the game pieces are thrown, it is evident that the player may construct the words, 90 Pig, Peg, Paw, Big, Bag, Baw, Jig, Jag and Jaw. In constructing the words from the various letters the player constantly refers to the words appearing in the central space 8 and should such words as may be constructed from the letters appear in this space, their numerical value is ascertained and by a process of addition the count of the individual players is made of record until he has a sufficient number to entitle him to 100 the game. However, should the player obtain a combination of letters from which it is possible to construct one of the words associated with one of the minus numerals it is evident that such player is required to deduct from his record the number associated with the word on the game board.

The marginal space 10 is divided by a series of relatively closely arranged radial lines into relatively narrow segmental spaces 110 14 in which is marked a multiplication table up to twelve times twelve and in each space

is also found the result of the multiplication indicated in the space. For instance, in the space in which appear the numerals three times three is found nine, the result 5 of such multiplication as in the space in which the numerals twelve times twelve appear the results or marks one hundred and forty-four, being the result of such multiplication.

- 10 For use in connection with the tables of multiplication there is provided a series of cubical game pieces 13 similar to those upon which the letters of the alphabet are marked and preferably four in number. Numerals 15 from 1 to 12 are printed or otherwise marked upon the surfaces of the cubical game pieces 13 and when persons not fully acquainted with the tables of multiplication are playing the game, the two numerals appearing upon 20 the four game pieces are employed in playing the game. For instance, if the numerals 10, 8, 6 and 5 appear upon the faces of the four game pieces when the latter are thrown, the player only selects the two lowermost 25 numerals, 6 and 5 which are multiplied together giving the player credit for thirty counts.

When fully qualified by experience and education, the players utilize the two higher 30 numbers in the playing of the game.

To render the playing of the game more difficult, instructive and interesting, certain of the relatively narrow spaces 14 contain various mathematical signs such as of addition, subtraction, multiplication and division. Should the numbers thrown by the player appear in one of the spaces 14 in which there is a mathematical sign, the player is required to carry out the mathematical problem. For instance, it will be assumed that one of the players is credited 35 with sixteen counts and throws the numerals 4, 4 on the game pieces. By reference to the game board it is evident that the 40 player is required to subtract the result of the multiplication of four times four from 45

his count thus leaving the player nothing to his credit.

If preferred, the cubical game pieces illustrated in Fig. 3 may be replaced by the 50 cards as suggested in Fig. 4 which may be printed or otherwise marked with the letters and numerals appearing on the cubical game pieces. When the game is played with the cards, it is carried on in substantially 55 the same manner as described in playing it with the cubical game pieces except that the cards are shuffled and dealt to the players.

What I claim is:

1. In a game apparatus, a board marked 60 off to provide a circular central space and segmental outer spaces, the outer spaces having certain letters of the alphabet thereon and the central circular space having a series of words thereon, the words being 65 identified by numerals indicating their value, and a plurality of game pieces having the other letters of the alphabet thereon not appearing on the board.

2. In a game apparatus, a board marked 70 off by circular and radiating lines into a central circular space and segmental spaces, the segmental spaces having letters of the alphabet marked thereon and the central space having a series of words thereon, the 75 words being identified by numerals representing their numerical value, and a plurality of game pieces having the letters of the alphabet thereon not appearing in the segmental spaces.

3. A game apparatus including a game board provided with a series of circular lines providing a plurality of segmental spaces, said spaces having the multiplication tables marked thereon, and a plurality 85 of game pieces having numerals thereon to be used in conjunction with the multiplication tables on the board to determine the count of the player.

In testimony whereof, I affix my signature hereto.

WALTER D. BRENNER.
